UNITED STATES PATENT OFFICE.

HENRY ALINDER, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

TWYER-VALVE.

1,118,613.

Specification of Letters Patent. Patented Nov. 24, 1914.

Application filed June 18, 1914. Serial No. 846,203.

To all whom it may concern:

Be it known that I, HENRY ALINDER, a subject of the King of Sweden, residing at Milwaukee, in the county of Milwaukee and 5 State of Wisconsin, have invented a certain new and useful Improvement in Twyer-Valves, of which the following is a specification.

This invention relates to improvements in 10 the construction of twyer valves of the type especially applicable to the twyers of converters or furnaces.

An object of the invention is to provide 15 a twyer valve for converters which is simple in construction and efficient in operation.

Another object is to provide a structure 20 in which the valve casing and housing are formed of a single casting of metal, thus forming a structure of maximum strength, eliminating necessity of extensively machining 25 the valve casing, and reducing the cost of production of the casing to a minimum.

Still another object is to provide a structure 30 in which the valve which is preferably of the ball type, is readily removable for inspection, from the casing.

A further object is to provide a device in 35 which the ball valve is retained within its housing within the valve casing when in operative position, by means of adjacent structural elements, the ball valve being freely removable from its housing by removal of the valve casing from its normal support.

It is well known to those skilled in the art 40 that ball valves are the preferred type of valve for use in closing the poke hole openings of converter and furnace twyers. In one of the structures of the prior art which utilizes ball valves in converter twyers, as disclosed in Patent 593,992, granted Nov. 23, 1897, the twyer box cap is provided with a 45 separate valve housing casing which is secured to the cap on the converter side thereof, by means of bolts or studs. In another of the structures of the prior art the valve cap is formed with an enlarged bore extending therethrough in line with the poke hole opening, this bore being bushed after insertion of the ball valve to prevent escape of the ball through the enlarged bore, see Patent 1,035,772, granted Aug. 13, 1913. The

50 ball may be removed in this type of valve by removal of the bushing. It has also been proposed as disclosed in Patent 1,034,995,

granted Aug. 6, 1912, to form the valve cap and housing in one piece and to cast the ball within its housing.

The structures of the prior art in which the ball valve is made removable by the provision of a separate ball retaining element such as a cap or bushing secured to the valve cap, are objectionable, first, because of the number of parts comprising the valve cap; second, because of the liability of loosening 60 of the separate retaining elements; third, because of the difficulty in removing the ball valve for inspection; and fourth, because of the enhancement in the cost of production of the valves due to the machining necessary 65 to properly connect the separate element to the cap. The structure in which the valve cap and housing are formed in one piece and in which the ball is cast directly within the housing, is objectionable 70 because of the destruction of the temper of the ball valve during the casting operation, and also because when once inserted 75 within its casing the ball cannot be removed for inspection without destruction of the 80 valve casing.

With the use of the present invention all of the above noted objectionable features are eliminated and a simple and efficient 85 valve casing may be produced at minimum cost.

A clear conception of an embodiment of the invention may be had by referring to the drawing accompanying and forming a part of this specification in which like reference characters designate the same parts 90 in the various views.

While the drawings disclose a converter twyer of the type in which a series of independent twyer boxes or casings are utilized, it should be understood that the invention is also readily applicable to structures in which a common twyer box is utilized for all of the valves.

Figure 1 is a transverse vertical section 100 through a converter twyer showing fragments of the wind box, converter shell and twyer pipe associated therewith. Fig. 2 is an end view of the twyer casing with the ball valve removed therefrom, the view being taken in the direction of the arrow A of Fig. 1.

Each of the converter twyers comprises a twyer casing 8, the interior of which is connected with the common wind box 6 by 110

means of suitable removable connections 7. The twyer pipe 9 is removably connected to the casing 8 and extends through an opening in the converter shell 11. The point of penetration of the shell 11 by the pipe 9 is provided with suitable packing which is inserted within the packing recess 12. The independent twyer valve casings 8 are each formed with a suitable recess at its lower extremity within which a bolt 13 coacts. The bolts 13 and their coacting nuts connect the twyer casings 8 with a spacing and supporting bar 14 which extends longitudinally of the converter shell 11. The bar 14 serves to properly space the independent twyers and to stiffen and form a proper support for the twyer casings 8.

The valve cap 2 is provided with a poke hole opening 3 which forms part of a through opening in the valve casing extending in the direction of, and in alignment with, the twyer pipe 9. The valve-housing wall 4 is formed in one with the valve cap 2 on the converter side thereof. This wall 4 is cut away at the portion 15 thereof which is in alignment with the poke hole opening 3, thus providing a continuous through opening or passage through the entire valve casing. An opening 10 is provided in the upper portion of the wall 4 and extends in a direction transverse to the direction of the poke hole opening 3. The ball valve 1, which is normally housed within the wall 4, and which controls the poke hole opening 3, is of such a diameter that it will not pass through the opening 15 in the wall 4 which is in alignment with the poke hole opening 3, but will pass freely through the opening 10 in the wall 4. The inner formation of the wall 4 is such that the ball valve 1 which is normally held against its seat by the air pressure within the casing 8, may be readily displaced from its seat over the poke hole opening 3 by the insertion of a rod through the poke hole opening, when the ball valve 1 will assume the position indicated in dot and dash lines in Fig. 1. The ball valve 1 is, however, prevented from leaving its housing within the wall 4 by the structural element adjacent the opening 10, this element in the present case being a portion of the twyer casing 8. The valve casing is held in position against the casing 8 by means of studs 5 and suitable retaining nuts coacting therewith, and forms a closure for the large opening in the end of the casing 8.

Upon removal of the nuts on the studs 5, the valve casing may be readily removed from the twyer casing 8, thus permitting ready removal of the ball valve 1 without necessitating removal of any special ball retaining elements connected to the valve cap 2. The formation of the wall 4 in one with the valve cap 2, eliminates necessity of machining the casting other than slightly

reaming or grinding the valve seat. The adjacent portion of the casing 8, which may, however, be any other structure which is independent of the valve casing, forms an efficient lock for preventing displacement of the ball valve 1 from within its housing. While the valve casing in the present instance is disclosed as forming a cap for the entire side of the casing 8, it should of course be understood that the valve casing 75 might be made only of sufficient size to properly house and form a seat for the ball valve 1. It should also be noted that the ball valve 1 need not necessarily control an opening 3 in the valve casing and that this 80 opening may be formed in other elements which do not form a part of the valve casing itself.

It should be understood that it is not desired to be limited to the exact details of 85 construction shown and described, for obvious modifications will occur to a person skilled in the art.

It is claimed and desired to secure by Letters Patent,—

1. In combination, a cap and a wall forming a one-piece valve casing, a ball valve within said casing, and a twyer coacting with said valve casing to lock said ball valve within said casing. 95

2. In combination, a twyer having an opening therein, a valve casing forming a closure for said twyer opening and having an opening therethrough to permit penetration by a bar, said valve casing forming 100 a receptacle for a ball valve and having therein a second opening free for the introduction of said valve to control said through valve casing opening, said casing coacting with said twyer to prevent displacement of 105 said valve through said valve casing opening.

3. In combination, a twyer casing, a cap and a wall forming a one-piece valve casing, and a ball valve within said valve casing and freely removable therefrom, said valve casing coacting with said twyer casing to form a housing for said valve and to permit said valve to control an opening into 110 said twyer casing. 115

4. In combination, a twyer casing having an opening therein, a valve casing forming a closure for said twyer casing opening and having an opening therein, and a ball valve freely insertable through said valve casing 120 opening, said valve casing opening being normally closed by adjacent structure of said twyer, and said valve casing coacting with said twyer casing to permit said valve to control an opening into said twyer casing. 125

5. As an article of manufacture, a valve casing having an opening therethrough to permit penetration by a bar, said valve casing forming a receptacle for a ball valve and having therein a second opening free 130

when said casing is removed from the twyer for the introduction of said valve to control said through opening.

6. In combination, a twyer casing having 5 an opening therein, a valve casing forming a closure for said opening, and a valve within said valve casing, said valve controlling an opening into said twyer casing and said casings coacting to form a housing for said 10 valve, said valve being freely removable upon removal of said valve casing from said twyer casing.

7. In combination, a twyer having an 15 opening therein, a cap and a wall forming a one-piece valve casing directly engaging said twyer to form a closure for said twyer opening, and a ball valve within said cas-

ing, said twyer coacting with said valve casing to lock said valve within said casing.

8. In combination, a one-piece twyer casing having an opening therein, a cap and a wall forming a one-piece valve casing directly engaging said twyer casing to form a closure for said opening, and a ball valve within said valve casing, said casings co- 20 25 acting to lock said valve within said valve casing.

In testimony whereof, the signature of the inventor is affixed hereto in the presence of two witnesses.

HENRY ALINDER.
